CARL H. BISSELL, OF SYRACUSE, NEW YORK, ASSIGNOR TO CROUSE-HINDS COMPANY,
OF SYRACUSE, NEW YORK, A CORPORATION OF NEW YORK.

MEANS FOR ATTACHING ELECTRICAL APPLIANCES TO CONDUIT OUTLET-BOXES.

1,223,467.

Specification of Letters Patent. Patented Apr. 24, 1917.

Application filed June 19, 1911. Serial No. 33,924.

To all whom it may concern:

Be it known that I, CARL H. BISSELL, of Syracuse, in the county of Onondaga, in the State of New York, have invented a certain new and useful Means for Attaching Electrical Appliances to Conduit Outlet-Boxes, of which the following is a specification.

This invention has for its object the production of means for attaching electrical appliances to conduit outlet boxes; and it consists in the combinations and constructions hereinafter set forth and claimed.

In describing this invention reference is had to the accompanying drawing in which like characters designate corresponding parts in all the views.

Figure 1 is a plan of one form of conduit outlet box provided with a preferable construction of my invention.

20 Fig. 2 is an elevation, partly in section, of a conduit outlet box provided with my invention, an electrical appliance as a lamp socket being shown attached thereto.

Fig. 3 is a longitudinal sectional view 25 taken at a right angle to Fig. 2.

Fig. 4 is a plan of the attaching means.

1 is the conduit outlet box which may be of any desirable form, size and construction, such box being here shown as having an 30 opening 2 in one side thereof and one or more internally threaded nipples 3 by means of which conduits containing electric wires are connected to the box 1.

The means for attaching the electrical appliance to the box 1 comprises a body for 35 engaging one face of the margin 4 of the wall around the opening 2, and having means fixed relatively thereto for engaging the opposite face of such margin and also 40 additional means spaced apart from the former means, the additional means being movably carried by the body and movable into and out of interlocking engagement with such opposite face of the margin 4.

45 The body 5 is preferably annular in general outline and engages the outer face of the margin 4, and is provided with fixed means for engaging the inner face of a portion of said margin. The fixed means engages the margin 4 at separated points 50 located in an arc concentric with the center of the body 5, and is here shown as a pair of lugs 6 located on one side of a diameter of the body 5, the lugs 6 being offset from the body 5 and preferably formed integral

therewith. The movable means is located on the opposite side of said diameter equidistant from said lugs and engages the opposite portion of the margin from that engaged by the lugs. Said movable means comprises a screw 7 arranged radially with the center of the body 5 and threaded through a lug 8 integral with the body 5 and extending inwardly through the opening 2, the said lug 8 being preferably arranged substantially opposite to a point midway between the pair of lugs 6 but spaced apart from the pair of lugs a distance greater than that between the members of said pair of lugs 6 substantially as shown in Fig. 4. The pair of lugs 3 act to hold the body rigid from lateral displacement in case the screw 7 is loose, and are the equivalent of a single lug of the same extent as the lugs 6 and the space between said lugs. 75

The body is also formed with inwardly extending and diametrically-disposed members 9 arranged in a plane substantially intermediate between the lug 8 and the members of the pair of lugs 6 and formed with 80 a plurality of pairs of screw holes 10, the holes of each pair of which are spaced the proper distance to receive the fastening screws as 11 of a commercial electrical appliance, it being understood that such screws 85 in different makes are spaced different distances apart. The electrical appliance is here shown as a lamp socket 12.

In placing this attaching means in position on the conduit outlet box, the body 5 90 of said means is positioned to rest on the margin of the wall around the opening of the outlet box with the lugs 6 extending under and engaging the inner face of such margin, the screw 7 is then turned so that it will 95 engage the inner face of said margin as shown in Fig. 3.

What I claim is:

1. The combination with a metallic outlet box having means for connection to a conduit, and an opening through one side of relatively large area, and an electrical appliance located outside of the box, of means for securing the base of the appliance to the side of the box provided with said opening, and with the major portion of the underside of said appliance in uninterrupted communication with the chamber in the box through said opening, said means comprising a flat ring seated upon the face of the 100 105 110

box surrounding the opening therein, said ring having a hook-shaped lug projecting from the inner edge thereof, and extending inwardly and outwardly for engaging the inner marginal wall of said opening in the box, a second lug extending from the inner edge of the ring at a point substantially opposite to the first lug, a screw adjustable transversely therein and designed to engage with the aforesaid marginal wall, and parts projecting from opposite sides of the inner edge of the ring, and located in a plane substantially intermediate between the lugs, and provided with openings for receiving means for securing said appliance to the ring, said ring and appliance constituting a closure for the opening in the box, substantially as and for the purpose described.

2. The combination with a metallic outlet box having means for connection to a conduit, and an opening through one side of relatively large area, and an electrical appliance located outside of the box, of means for securing the base of the appliance to the side of the box provided with said opening, and with the major portion of the under side of said appliance in uninterrupted communication with the chamber in the box through said opening, said means comprising a flat ring seated upon the face of the box surrounding the opening therein, said ring having a pair of spaced apart hook-shaped lugs

projecting from the inner edge thereof, and extending inwardly and outwardly for engaging the inner marginal wall of said opening in the box, a third lug extending from the inner edge of the ring at a point substantially opposite to a point midway between the pair of lugs, said third lug being spaced apart from the pair of lugs a distance greater than that between the members of said pair, a screw adjustable transversely in the third lug and designed to engage with the aforesaid marginal wall, and parts projecting from diametrically opposite sides of the inner edge of the ring, and located in a plane substantially intermediate between the third lug and the members of the pair of lugs, and provided with openings for receiving means for securing said appliance to the ring, said ring and appliance constituting a closure for the opening in the box, substantially as and for the purpose described.

In testimony whereof, I have hereunto signed my name, in the presence of two attesting witnesses, at Syracuse, in the county of Onondaga, in the State of New York, this 14th day of June, 1911.

CARL H. BISSELL
